UNITED STATES PATENT OFFICE

169,363

TELEVISION CABINET

Franklin H. Ellison, Brooklyn, N. Y.

Application July 24, 1951, Serial No. 16,007

Term of patent 14 years

(Cl. D56—4)

To all whom it may concern:

Be it known, that I, Franklin H. Ellison, a citizen of the United States, residing at Brooklyn, in the county of Kings and State of New York, have invented a new, original, and ornamental Design for a Television Cabinet, of which the following is a specification, reference being had to the accompanying drawing, forming part thereof.

The single figure shown is a perspective view of a television cabinet, embodying my new design.

I claim:

The ornamental design for a television cabinet, as shown.

FRANKLIN H. ELLISON.
